UNITED STATES PATENT OFFICE.

JOHN L. MOHUN, OF BROOKLYN, NEW YORK, ASSIGNOR TO THE FRANKLIN RAILWAY SUPPLY COMPANY, OF WILMINGTON, DELAWARE, A CORPORATION OF DELAWARE.

FURNACE-DOOR DEVICE.

1,235,228.

Specification of Letters Patent. Patented July 31, 1917.

Application filed March 6, 1914. Serial No. 822,855.

To all whom it may concern:

Be it known that I, JOHN L. MOHUN, a citizen of the United States, residing at Brooklyn, in the county of Kings and State 5 of New York, have invented a certain new and useful Improvement in Furnace-Door Devices, of which improvement the following is a specification.

This invention relates to fire door devices 10 for furnaces, and more particularly for locomotive boilers, the principal object being to provide an improved door construction of the inside vertically swung type, in which the door is normally closed against the 15 frame from within by gravity, and is adapted to swing bodily inward and upward in its opening movement to a position above the door opening.

According to a preferred construction, the 20 door is provided with a supporting arm rigidly attached to the door and extending outward and upward to a horizontal shaft or pivot supported above the door opening. By this means the door may be automatically 25 closed by gravity without shock, as the center of gravity of said door is nearly in vertical line with the supporting shaft, when the door reaches its closed position.

Another object of my improvement is to 30 provide a deflecting baffle plate supported upon the outer side of the door in such position that the same serves as a deflector to direct the draft of air downward, and away from the boiler flues when the door is in its 35 open position.

Another feature of my improvement relates 40 to an improved fluid pressure cylinder and piston for operating the door, which may be placed vertically at the side of the door and connected by a crank with the horizontal shaft on which the door swings. Another feature comprises an improved 45 handle mechanism and pawl and ratchet device for manually operating the door and for coöoperating with its operation by the fluid pressure motor. Still another feature 50 comprises the use of a supply of compressed air or steam for actuating the motor and an improved three-way valve device for controlling the same; and a further object is to provide an improved admission valve located within the cylinder head where it is thoroughly protected.

These and other features of my improve-

ment will now be more fully described in detail.

In the accompanying drawing: Figure 1 is a front elevation of a furnace door device embodying my improvement, the motor cylinder being shown in vertical section; Fig. 60 2, a longitudinal vertical section, taken on the line 2—2 of Fig. 1; Fig. 3, a transverse section of the supporting shaft and a portion of the handle for manually operating the door; Fig. 4, a similar transverse section 65 of the shaft showing the pawl and ratchet device for holding the door at its different positions; Fig. 5, a vertical section of the motor cylinder head taken on the line 5—5 of Fig. 1; and Fig. 6, a section of the three-way valve device for controlling the supply 70 of either compressed air or steam for actuating the motor.

According to the construction shown in the drawings, my improvement is applied to 75 a locomotive boiler furnace, and comprises a door frame, 7, bolted to the back head, 8, of the locomotive boiler around the firing opening, the frame being formed with a curved portion, 9, extending inward through 80 said opening, and terminating with an edge having its face inclined from the inside of the furnace wall at the top of the frame outward toward the bottom, and against which face the door, 10, normally rests when in its 85 closed position. The door is supported by an arm, 11, one or more, rigidly attached to the outer face of the door, preferably at a point below its upper edge, and extending outwardly and upwardly to a horizontal 90 shaft, 12, mounted in bearings in brackets, 13, formed on the frame above the door opening. The supporting arm is conveniently mounted on the shaft and is preferably curved so that when the shaft is turned, 95 the door swings bodily inward and upward to its open position above the firing opening, as indicated in dotted lines in Fig. 2. A baffle plate, 14, is mounted on said arm upon the outer side of the door in such position 100 and at such an angle to the plane of the door as to deflect the current of air downward and away from the boiler tube sheet when the door is open, as shown in dotted lines, Fig. 2.

According to another feature of my invention, the door is operated by a fluid pressure motor comprising a vertical cylinder,

15, supported on the frame at the side of the door, and containing a piston, 16, connected by a pitman, 17, with a crank, 18, on the end of the horizontal shaft, 12. The piston occupies its lowermost position when the door is closed, and a spring, 37, is also employed for assisting in holding the door in its closed position, as the suction produced within the fire box by means of the engine 70
10 exhaust is sometimes so great as to tend to open a furnace door of this inwardly swinging type. The piston rod, or pitman, and crank are inclosed within a casing, 19, for protecting the moving parts, and excluding 15 dirt and dust.

15 The admission valve, 21, for controlling the operation of the motor is preferably located in the cylinder head, 20, and controls communication from supply passage, 23, to 20 port, 24, leading into the cylinder, and also the exhaust therefrom through port, 25, the projecting stem, 22, of the valve being adapted to be operated by a pedal device or other suitable or preferred mechanism not 25 shown.

Either steam or compressed air may be employed to operate the motor and according to one of the features of my improvement, I provide a steam supply pipe, 26, and 30 a compressed air supply pipe, 27, with a three-way valve, 28, for turning on either one and cutting off the other. Check valves, 29 and 30, are also provided in the respective pipe connections, in order to prevent the back flow through either pipe when the fluid supply is being used from the other, such as might result in case of leakage around the valve.

For the purpose of operating the door 40 manually, a handle, 31, is loosely mounted on the shaft, 12, and a ring, 32, having a lug is fixed upon the shaft in such position as to be engaged by the handle when the same is turned a certain distance, and there- 45 by actuate the shaft and open the door. The handle is counterbalanced at 33, in order to hold the same normally out of contact with the lug ring, 32, as shown in Fig. 3. The door may be set in a partial or full open 50 position by means of the ratchet wheel, 34, fixed upon the shaft, 12, and having a plu- 55 rality of notches, and a pawl, 35, pivoted upon the frame, as shown particularly in Fig. 4. The pawl is weighted at 36, so as to normally disengage the ratchet teeth or notches, but is adapted to be raised by hand and engage either one of said notches when it is desired to hold the door either partially or fully open.

60 When fluid pressure is admitted to the cylinder, the piston is forced upward against the spring, 37, turning the crank and shaft, and thereby swinging the arm, 11, and door, 10, upward to the open position. When the 65 fluid is exhausted from the cylinder, the

door automatically closes by gravity, assisted by the spring, 37. If the door should be latched partially open by means of the pawl at the time that fluid is supplied to actuate the motor, the ratchet is immedi- 70ately released and the pawl drops out of en- gagement by gravity. The handle remains in its normal vertical position and does not interfere with the operation of the device by fluid pressure.

If the door is latched by the pawl and ratchet in the full open position, the admission of fluid pressure to the cylinder will not release the pawl, as the piston is already moved to its highest point, and the door 80 will then remain at its full open position.

It will now be apparent that this im- 85 proved construction may be readily applied to any locomotive, as no additional clear- 90ance space around the door is required for its movement. As the control valve is located in the cylinder head, all piping be- 95tween the valve and cylinder is dispensed with, thereby economizing the amount of fluid required, reducing the liability of leak- 90age, and protecting the valve from injury. Either steam or compressed air may be em- 95ployed to operate the motor and in case of the failure of one of these agents, the other may be used. The check valves will pre- 100vent steam from flowing back through the pipe to the air brake system, or compressed air from entering the boiler in case the pressure therein should be sufficiently low, and if there should be considerable leakage around the three way cock.

As the door closes against the inner edge of the frame, it cannot easily be blown open from a pressure within the fire box, and this feature adds to the safety of the en- 105gineer and fireman in case of a burst boiler flue or other similar accident. The construction is comparatively simple, light and durable, composed of few parts, cheap to manu- 110facture and maintain, and reliable in op- 110eration.

Having now described my invention, what I claim as new and desire to secure by Let- 115ters Patent is:

1. In a furnace door device, the combina- 115tion with a metal frame adapted to be bolted to the back head of the boiler, and having a curved wall portion extending inward through the firing opening, said curved wall portion terminating in an edge having its 120 face inclined from the top outwardly to- 125ward the bottom, of an inwardly and up- 125wardly swinging door normally seated against said face in its closed position, brackets on said frame above the door open- 130ing, a horizontal shaft having bearings mounted in said brackets, and a supporting arm rigidly attached to the lower part of the door and extending outwardly and up- 130wardly to said shaft.

2. In a furnace door device, the combination of an inwardly swinging door having an outwardly and upwardly extending supporting arm, and a baffle plate mounted at 5 an angle upon the outside of said door and adapted to deflect the air draft when the door is open.
3. In a furnace door device, the combination of a frame, an inside vertically swung 10 door closing against said frame in a position inclined outwardly at the bottom, a horizontal shaft mounted outside and above said door, a supporting arm extending outwardly from said door and mounted on said shaft, 15 and a baffle plate mounted on the outside of the door for deflecting the air draft when the door is open.
4. In a furnace door device, the combination of a frame, an inside vertically swung
- door closing against said frame, a horizontal 20 shaft mounted outside and above said door, a supporting arm mounted on said shaft, and attached to the door, and a deflecting baffle plate supported upon said arm on the outside of said door.
5. In a furnace door device, the combination with a door and a cylinder and piston for operating the same, of a steam supply pipe and an air supply pipe for said cylinder, a three-way valve for controlling communication from either of said pipes to the cylinder, and check valves for preventing back flow in either of said pipes when fluid is being used from the other.
